UNITED STATES PATENT OFFICE.

JAMES D. CONEY, OF DETROIT, MICHIGAN.

GARMENT-SUPPORTER.

1,070,668.

Specification of Letters Patent. Patented Aug. 19, 1913.

Application filed December 17, 1910. Serial No. 597,775.

To all whom it may concern:

Be it known that I, JAMES D. CONEY, a citizen of the United States, residing at Detroit, county of Wayne, State of Michigan, have invented a certain new and useful Improvement in Garment-Supporters, and declare the following to be a full, clear, and exact description of the same, such as will enable others skilled in the art to which it pertains to make and use the same, reference being had to the accompanying drawings, which form a part of this specification.

My invention has for its object to provide a simple and novel device for supporting garments of various kinds when not in use in such a way as to preserve their shapes.

The various features of novelty whereby my invention is characterized will herein-after be pointed out with particularity in the claim; but for a full understanding of my invention and of its object and advantages, reference may be had to the following detailed description taken in connection with the accompanying drawing, wherein:

Figure 1 is a side elevation of a device arranged in accordance with a preferred form of my invention; and Fig. 2 is a top plan view of said device.

In accordance with my invention I make use of a hanger having associated therewith resilient members which will yield to adjust themselves to a garment supported thereon so as not to draw the garment out of shape. I prefer to make the hanger in the form of a resilient cross piece provided with a suspending member and having inwardly and upwardly projecting yielding arms which are free at their inner ends so as to enable them to assume various positions in service.

Referring to the drawing, A represents a cross piece having at the middle a suspending member B, these two members constituting the hanger. Secured to the ends of the cross piece are arms C extending upwardly and inwardly into proximity to the upper end of the suspending member, but unattached to the suspending member at their inner ends. The arms are preferably curved so as approximately to follow the contour of the shoulders and the collar portions of a coat, waist or the like. I prefer to make the arms resilient so that they can yield under a superposed load and adapt themselves to the shape of a garment without

producing any distortion in the latter. I also prefer to make the cross piece yieldable so that the ends thereof may droop when a garment of any considerable weight is placed on the supporter. The resiliency of the arms and of the cross piece affords a double yielding action which gives the supporter capacity to shape itself to garments of various contours and sizes.

In the arrangement shown I have formed the supporter of wire and therefore, in order to give the cross piece strength without using too heavy a wire and at the same time make the cross piece resilient, I bend each half of the cross piece into a loop between the ends thereof, as indicated at D, D, and join the loops by a tie member E. The tie member stiffens the central portion of the cross piece so as to make it capable of sustaining a considerable weight and leaves the extreme ends resilient. The resiliency of the ends of the cross piece is increased by the spring action of the loops.

Where the supporter is made of wire the arms C may conveniently be formed by bending up the free ends of the cross piece. In the arrangement shown the members A, B and C are all formed of a single piece of wire and I consider this the preferred form, although it is evident that my invention is not limited to this particular construction. Where the supporter is made of a single piece of wire, the wire is first doubled in the middle so as to form the suspending member, and it may then be twisted together as at b at the lower end of the suspending member. The two ends of the wire are then bent laterally in opposite directions, each being bent so as to form one of the loops D and the free ends are then carried inwardly and upwardly and back again to the ends of the cross piece where they are secured, thus giving the spring arms the form of elongated loops. Below the cross piece there may be arranged a secondary supporting member F comprising a U-shaped piece having its arms secured to the cross piece. The member F is preferably made of wire whose ends are looped about the cross piece so as to permit the member F to be swung about the cross pieces and axis and be folded up against the suspending member for shipment.

Skirts or trousers may be folded and hung over the member F, keeping their position

by being balanced thereon. It may sometimes be desirable to carry about the supporter while it is loaded with garments and therefore I have provided a locking device 5 for the garments suspended on the member F so as to prevent displacement of such garments. The locking device need not be used unless it is desired, it being understood that my invention is not limited to a sup- 10 porter having a locking device. The locking device may conveniently be made in the form of a member G similar to a key ring but having its turns g and g' separated somewhat so as to form a jaw; one end of 15 the member G being carried radially to form a stem g^2 . The free end of the stem may be provided with a ring g^3 which is large enough to pass freely over the suspending member B. When the locking de- 20 vice is not in use it may be lifted and the member G hooked over the cross piece or tie member E. When it is desired to lock a garment upon the member F, the locking device is dropped down into the position 25 indicated in Fig. 1, engaging the fold in the garment upon the member F in the same

way that a clothes pin fastens a garment to a line.

While I have illustrated and described with particularity only a single form of 30 my invention I do not desire to be limited to the specific details as illustrated and de- scribed; but intend covering all construc- 35 tions and arrangements which fall within the terms employed in the definitions of my invention constituting the appended claim.

What I claim is:

A garment supporter comprising a wire cross-piece having a suspending member at the middle, each half of the cross-piece being bent into a loop between the ends thereof, a tie connecting the two loops, and arms extending from the free ends of the cross piece upwardly and inwardly toward the suspending member. 40

In testimony whereof, I sign this specification in the presence of two witnesses.

JAMES D. CONEY.
